PRINTING MACHINE

Elmer T. Knitter, Redwood City, Calif.

Application September 18, 1945, Serial No. 617,026

5 Claims. (Cl. 41—7)

1

My invention relates to apparatus for stamping or embossing, and more particularly, to a machine useful for applying monograms, initials, or other legends to objects such as playing cards, pencils, or any of a host of similar articles.

Hitherto machines useful for work of this kind have been relatively complicated and expensive in addition to being operable only by highly skilled persons. Hence it has been the general custom of manufacturers to apply legends to articles at the factory and supply to the retail outlets complete sets of monogrammed articles. The result has been unsatisfactory since it is impossible accurately to predict what initials or legends will be most in demand.

The most important object of the present invention is to provide a simple, efficient machine, capable of being used by unskilled persons and by means of which small articles may be rapidly stamped or embossed in the retail store to suit the demands of the individual customer while the customer waits.

A further object of my invention is to improve the quality and accuracy of an embossing machine.

Still another object of my invention is to reduce the cost of an embossing or stamping machine to such an extent that it becomes economically practical to install such machines in retail stores.

One feature of my invention resides in an automatic clutch control which is operated upon the insertion in the machine of an article to be stamped or embossed and which causes the machine to effect one complete cycle and then stop.

Another feature of the invention consists in mechanism capable of automatically pressing an embossing tape upon an article, ejecting the embossed article, and advancing the tape one step to prepare the machine for a subsequent operation.

Still another feature of the invention comprises mechanism capable either of automatic operation upon articles of predetermined dimension or of manual operation upon articles of irregular or unusual size.

In brief, the machine of my invention includes a support for an object to be stamped, a carriage upon which a die, stamp, or type is mounted, mechanism for feeding tape from a reel across the top of the support, and driving mechanism for moving the carriage toward the support, where the tape is pressed against an article. Furthermore, in the cycle of the machine the tape is automatically advanced one step after

2

each stroke of the carriage, and an ejector is actuated to remove the stamped object from the support.

These and other objects and features of my invention will be more readily understood and appreciated from the following detailed description of a preferred embodiment being selected for purposes of illustration and shown in the accompanying drawings, in which:

Fig. 1 is a view in perspective of a machine embodying my invention;

Fig. 2 is a view partly in side elevation and partly in cross-section of the machine shown in Fig. 1;

Fig. 3 is a view in cross section along the line 3—3 of Fig. 4;

Fig. 4 is a view in cross-section along the line 4—4 of Fig. 3;

Fig. 5 is a view in cross-section through the clutch mechanism;

Fig. 6 is a view in perspective of the clutch-control and ejector mechanisms;

Fig. 7 is a view in perspective showing details of the pencil support;

Fig. 8 is a view in cross section along the line 8—8 of Fig. 11;

Fig. 9 is a view in end elevation of the clutch-control trip mechanism, parts being broken away to show details thereof;

Fig. 10 is a view in cross-section along the line 10—10 of Fig. 11; and

Fig. 11 is a view in cross section along the line 11—11 of Fig. 10.

Before proceeding to a detailed description of the elements of the machine shown in the drawings, I shall discuss briefly the instrumentalities of primary significance and explain their interrelation.

Upon the forward end of the base 11 of the machine is provided a space for support of an object to be stamped. For example, in Fig. 10 a playing card 150 is shown partially inserted on the support. Poised above the support is a carriage 68 on the end of which is mounted a heated embossing die 83, and a strip of tape 96 is shown positioned between the die and the support. Behind the support for the card 150 is shown an ejector 128.

In the operation of the machine the carriage 68 is driven downwardly to carry the die 83 into engagement with the tape 96. Subsequently the die presses the tape firmly against the upper surface of the card 150. The tape 96 is gilded, silvered or otherwise colored, and the pressure of the heated die 83 effects an embossing of the

3 back of the card 150. In the following portions of the cycle of the machine, the carriage 68 is moved upwardly, the tape 96 is advanced a predetermined distance to present a fresh portion thereof beneath the die 83, and the ejector 128 is operated to kick the card 150 from the support.

4 The machine may be secured to a counter or bench or, if it is desired to render the machine portable, it may be mounted on a wooden block 10. The machine is organized about a metal base plate 11 and a frame comprising a pair of upstanding parallel walls 12 and 13 secured to opposite sides of the base plate 11. At their upper ends the walls carry a rectangular member 14 which forms, with a cover plate 15, a housing 16 containing a power supply switch 17 and an electric socket 18 for the electric cord to the heating element 84.

An electric motor 20 is mounted on four legs 21 which are secured to the base 11. Upon the outer end of the motor shaft 22 a worm 23 is fixed in position to mesh with a worm wheel 24 mounted for free rotation upon a shaft 30 journaled in the walls 12 and 13 of the machine frame. Fast to the worm wheel 24 is a clutch disk 25 having a large central recess in one face including in its periphery a series of re-entrant notches 26 arranged as the points of a star. A disk 27, keyed to the shaft 30, carries a pivotally mounted pawl or cam 28 normally urged into engagement with one of the notches 26 by a compression spring 31. The disk 27, the cam 28, and the member 25 comprise a clutch operable to couple the shaft 30 to the worm wheel 24.

To control the operation of the clutch I have employed mechanism including a rock shaft 33 journaled in a pair of upstanding ears or lugs 32 secured to the base 11 and carrying a plate 36 cut to fit the contour of the disk 27 and carrying a stop bar 37. On one end of the rock shaft 33 is mounted a pin 34 carrying a weight 35 so arranged as to rock the stop 37 into position to engage the pawl 28 and pivot it out of contact with the notches 26. The shaft 30 is then uncoupled from the worm drive. At the other end of the shaft 33 there is mounted a pin 41 extending downwardly into a hole cut in the base 11 (see Fig. 9). Also, the shaft 33 carries a collar 38 provided with an integral lug 39 upon which bears the lower end of a plunger 40. It will be evident that the shaft 33 may be actuated either by movement of the pin 41 or of the plunger 40. Such motion frees the cam 28, permitting it to engage one of the notches 26 and start the shaft 30 turning. If the weight 35 is now allowed to rock the shaft 33 to initial position, the stop bar 37 will engage the cam 28 when it has traveled 360 degrees and then stop the motion of the shaft 30.

It is contemplated that the clutch be actuated by the insertion of an article in the machine. As shown in Figs. 9 and 10, a playing card 150 is placed upon the base 11 in an area protected by a safety guard rail 46. As the card travels along the base 11 it encounters a ball bearing 45 held in an inverted cup 44 carried by a bracket 43 secured to the base 11. The ball bearing 45 holds the card 150 flat upon the base 11. When the card 150 reaches a predetermined position it engages the pin 41, and movement of the card to final position causes the pin 41 to rock the shaft 33 and trip the clutch.

Referring now to Figs. 2 and 4, I have shown a disk 47 mounted eccentrically on the shaft 30 and arranged to turn in the hub of a pitman 48

5 the upper end of which terminates in a clevis 49. A cross pin 54 works in opposed slots 53 cut in the side members of the clevis 49, and a plunger 52 seated in a hole 51 cut in the pitman is urged by a spring 53 against a lever 55 pivotally mounted on the pin 54. The lever 55 is secured to a bracket 56 pivotally mounted on a stub shaft 57 carried by the frame walls 12 and 13. It will now be evident that rotation of the shaft 30 acting through the eccentric and pitman causes the lever 55 to rock about the stub shaft 57.

6 Projecting from the walls 12 and 13 is a pair of parallel arms 58 joined at their outer ends by a cross piece 61 and carrying a cover plate 60. These members form a frame or housing through which the plunger 40 extends. A spring 59, encompassing the upper end of the plunger 40 and bearing upon the plate 60 and an enlarged head 19 on the plunger 40, serves to prevent the plunger 40 from actuating the clutch control shaft 33 until sufficient force is brought to bear on the head 19 to cause the plunger to depress the lug 39.

Secured to the cross piece 61 is a pair of vertical parallel guide bars 64 between which slides 25 a bar 65. A cross bar 63 extending between the arms 58 serves as a rear guide for the bar 65. A bolt 67 engages a hole tapped in the upper end of the bar 65 and bears against a spring-depressed friction pin 66. The bolt 67 serves to determine the depth of movement of the bar 65. The pin 66 prevents the bolt 67 from turning of its own accord. The outer end of the lever 55, in its stroke, drives the bar 65 downwardly, and a tension spring 70 secured to the cross-piece 35 61 and the bar 65 serves to return the bar 65 when the upper end of the lever 55 is moved upwardly.

The bar 65 carries a rack 71 engaging a pinion 72 fast upon a shaft 73 mounted in a pair of 40 brackets secured to the guide bars 64. On the outer end of the shaft 73 there is a pin 69 working in a clevis on the end of a handle 75. The shaft 73 is free to rock without moving the handle, but if the handle 75 is rocked to the left (see Fig. 1), the shaft 73 turns, and the pinion 72 forces the rack 71 and the bar 65 downwardly against the action of the spring 70. When the handle is released, the spring 70 returns the bar 65 to its initial position. A stop pin 76 secured to the wall 13 limits motion of the handle 75.

As shown particularly in Fig. 2, a base member 77 is secured to the bottom of the sliding bar 65 by a screw 78, and a pair of L-shaped members 80 secured to the base 77 form guides for a die holder 81 having downwardly extending parallel flanges for clamping a stick of type. The type is shown at 83 and the slug or type base is shown at 82. The bar 65, the base 77, and 60 the members 80 may be considered as a carriage, which I have denoted by the general reference numeral 68. Any suitable die, stamp, embossing tool, or type may be mounted on the end of the bar 65, and it is contemplated that the operator 65 of the machine will have at hand complete alphabets of various styles of monograms, initials, legends, or ornamental devices. A suitable length of high resistance wire 84 such as Nichrome, is arranged about the base 77 in order 70 to heat the stamp or die electrically and produce an effective embossing or stamping of an article.

A bracket 90 secured to the wall 13 supports a horizontal rod 91 which carries a reel 92. The reel is secured against lateral displacement by a 75 collar 93 fast upon the outer end of the rod 91.

and by a spring 94 bearing against the reel and a second collar 95 secured to the rod 91. The reel may conveniently be wound with ordinary embossing tape 96, either gilt, silver, or other suitable color. The tape 96 is led from the reel 92 down beneath the guard rail 46 and up on the other side of the machine to a step-by-step feed mechanism by means of which the tape 96 is advanced between the article support on the base 11 and the die or stamp carried by the carriage 68.

Secured to one of the arms 58 is a U-shaped frame member 97 in which is journaled a stub shaft 98 carrying a rubber feed roll 100. The frame 97 also loosely supports a second stub shaft 101 mounted above and parallel to the shaft 98. A metal roll 102 secured to the shaft 101 has a pair of knurled flanges cooperating with the feed roll 100. A plate 103 is forked to provide two arms 104 bearing on the stub shaft 101 and has a downwardly extending portion 105. A spring 106 connected to the portion 105 and the frame 97 serves to urge the arms 104 against the shaft 101 to press the upper feed roll 102 into contact with the rubber roll 100. The shaft 98 is prevented from lateral displacement by a pair of collars 108 which bear against the frame 97. A handle 107 is carried on one end of the shaft 98 and provides means whereby the tape 96 may be manually fed.

On the other end of the shaft 98 is a loose collar 110 having an integral lug carrying a pivotally mounted pawl 111 which normally engages a ratchet wheel 109 keyed to the shaft 98. A pin 112 mounted on the frame 97 provides a pivotal mount for a second pawl 113 urged against the ratchet by means of a spring (not shown). Pawl 113 prevents the rubber roller 100 from backing up.

One end of a turnbuckle 114 is pivotally connected to the collar 110, and the other end thereof is pivotally mounted at one end of a lever 115 which traverses the machine and connects pivotally to another lever 116 secured to one of the guide bars 64. The lever 115 rests against a stop 117 secured to the carriage 68. When the carriage descends, the stop also lowers and permits the lever 115 to drop. This motion retracts the pawl 111 along the ratchet 109. When the spring 70 moves the carriage 68 upwardly, the stop 117 lifts the lever 115 and causes the pawl 111 to turn the ratchet wheel 109. The feed rolls 100 and 102 then operate to advance the tape 96.

In order to control the rate at which the tape is advanced during a cycle of the machine, I provide a stop bar 118 slidably mounted on one of the brackets 74 and maintained in position by means of a spring-pressed clamp 129. The bar 118 is widened at its lower end to provide a shoulder 118a (see Fig. 2) arranged to lie in the path of the falling lever 115. By adjusting the bar 118 up or down the motion of the pawl 111 is determined and the rate of feed of the tape 96 thereby controlled. It is evident that the feeding motion begins shortly after the carriage 68 starts its upward movement.

The ejector mechanism will now be described with particular reference to Figs. 2, 4, and 6. Keyed to the shaft 38 is a cam 119 arranged to strike a follower 120 carried by a lever 121 pivotally mounted on a pin 122 carried on the inner surface of the wall 13. A second lever 123 is pivotally connected to the lever 121 and to a lug 124 forming an integral part of a plate 125. The plate 125 has a centrally located elongated slot 75

126 through which extend a pair of bolts 127 mounted in the base 11 and carrying springs about their shanks to urge the plate 125 against the flat surface of the base 11. One end of the plate 124 is bent upwardly to form a flange 128. A spring 130 is connected to a screw 131 mounted on the base 11 and to the plate 124. As the shaft 38 turns, the cam 119 acts through the levers 121 and 123 to push the plate toward an article held under the ball bearing 45. The flange 128 ejects the article from the base 11 and it falls into a receptacle 132 carried by a pair of pins 134 on the block 10. After the cam 119 has passed by the follower 120, the spring 130 returns the ejector to its initial position.

The machine as described above is set up particularly to emboss a playing card 150 or a similar flat article. A ledge 42 on the base 11 serves to position the card for embossing or stamping.

When it is desired to stamp an article such as a pencil, a special holder or support 135 is placed on the base as shown in Fig. 7. The support is provided with a depending front plate 137 which engages the front face of the base 11 and an inwardly extending flange 138 engages the ledge 42 to ensure proper positioning of the holder 135. A pencil 136 is shown in the holder beneath the downwardly traveling carriage 68.

When cards are to be stamped, the machine is automatically tripped by the impingement of a card against the pin 41. Otherwise the machine may be placed in motion by pressing the plunger 40. When articles of irregular or unusual dimensions are to be embossed the handle 75 may be used to move the carriage 68 the proper distance.

Those skilled in the art will readily appreciate that the machine shown and described is but one possible embodiment of my invention. Many variations will be apparent, but the invention is to be measured by reference to the appended claims.

Having thus described and illustrated my invention, what I claim as new and desire to secure by Letters Patent of the United States is:

1. A stamping machine, including in combination a frame; a support for an article to be stamped, adjacent said frame; a drive shaft; means to rotate said drive shaft; a second shaft mounted in said frame; clutch means, including a pawl keyed to said second shaft, for operatively connecting said drive shaft to rotate said second shaft; means normally urging said pawl into a position when said clutch is engaged; means including a weighted rocker shaft, to urge said pawl into a non-engaging position; a lever system operated when an article is positioned in said support in its correct stamping position to counteract said last-named means and permit said pawl to engage said clutch means for one 360° turn; a die-carrying carriage mounted above said support in said frame for movement toward and away from said support; means urging said carriage normally upwards; eccentric means operated by said second shaft to move said carriage down against an article placed in said support; means on said frame for mounting a roll of embossing tape; means on said frame to pull said tape between said support and said carriage and out from between them; ratchet means on said tape-pulling means for moving said tape in only one direction; and a lever system actuated by said carriage to slip said ratchet during the down stroke of said carriage and engage said ratchet and move it during the up stroke thereof.

2. A stamping machine, including in combination a frame; a support for an article to be stamped, adjacent said frame; a drive shaft; means to rotate said drive shaft; a second shaft mounted in said frame; clutch means, including a pawl keyed to said second shaft, for operatively connecting said drive shaft to rotate said second shaft; means normally urging said pawl into a position when said clutch is engaged; means including a weighted rocker shaft, to urge said pawl into a non-engaging position; a lever system operated when an article is positioned in said support in its correct stamping position to counteract said last-named means and permit said pawl to engage said clutch means for one 360° turn; a die-carrying carriage mounted above said support in said frame for movement toward and away from said support; means urging said carriage normally upwards; eccentric means operated by said second shaft to move said carriage down against an article placed in said support; means on said frame for mounting a roll of embossing tape; means on said frame to pull said tape between said support and said carriage and out from between them; ratchet means on said tape-pulling means for moving said tape in only one direction; a lever system actuated by said carriage to slip said ratchet during the down stroke of said carriage and engage said ratchet and move it during the up stroke thereof; and a cam keyed to said second drive shaft, an ejecting means reciprocated horizontally by said cam to eject said article from said support after it has been stamped.

3. A stamping machine, including in combination a frame; a support for an object to be stamped, adjacent said frame; a carriage supported above said support for reciprocation in said frame toward and away from said support; means for urging said carriage normally upward; a die mounted on said carriage; means secured to said frame for supporting a roll of embossing tape; means for feeding a predetermined amount of said tape from said roll between said die and said support on the upward stroke of said carriage; means for ejecting an object from said support; a drive shaft mounted in said frame; means to rotate said drive shaft; a clutch capa-

ble of employing said drive shaft to give the power to lower said die to press said tape against said object, and then to release said die and allow it to pass upward, and the power to operate during said upward stroke said ejecting means; and a lever operated by the object to be stamped to move said clutch to its engaging position.

4. A stamping machine, including in combination a frame; a support for an article to be stamped, adjacent said frame; a drive shaft; means to rotate said drive shaft; a second shaft mounted in said frame; clutch means, including a pawl keyed to said second shaft, for operatively connecting said drive shaft to rotate said second shaft; means normally urging said pawl into a position where said clutch is engaged; means including a weighted rocker shaft, to urge said pawl into a non-engaging position; a lever system operated when an article is positioned in said support in its correct stamping position to counteract said last-named means and permit said pawl to engage said clutch means for one 360° turn; a die-carrying carriage mounted above said support in said frame for movement toward and away from said support; means urging said carriage normally upwards; eccentric means operated by said second shaft to move said carriage down against an article placed in said support; a cam keyed to said second drive shaft, an ejecting means reciprocated horizontally by said cam to eject said article from said support after it has been stamped.

5. The machine of claim 3 in which there is an electrically energized heating unit mounted in said carriage adjacent said die, whereby said die is heated for transferring pigment from said embossing tape to said object.
